UNITED STATES PATENT OFFICE.

ORRELL ASHTON, OF LAWRENCE, MASSACHUSETTS, ASSIGNOR TO UNITED SHOE MACHINERY COMPANY, OF BOSTON, MASSACHUSETTS, A CORPORATION OF NEW JERSEY.

QUILTING-MACHINE.

1,019,118.

Specification of Letters Patent.

Patented Mar. 5, 1912.

Application filed May 16, 1901. Serial No. 60,529.

To all whom it may concern:

Be it known that I, ORRELL ASHTON, a citizen of the United States, residing at Lawrence, in the county of Essex and State 5 of Massachusetts, have invented an Improvement in Quilting-Machines, of which the following description, in connection with the accompanying drawings, is a specification, like letters on the drawings representing like parts.

This invention has for its object the production of a novel machine for inserting wire or like material in stock.

The machine is particularly intended for 15 that kind of work called quilting, but the invention is not limited to such work, as it is capable of other useful application.

My improved machine contains a work support having a throat through which a 20 feeding device operates, said feeding device engaging the work lying on said work support and feeding the work for the distance desired between adjacent fastenings. The work support and the feeding device, herein 25 represented as a wheel, are yieldingly sustained that they may rise and fall together to enable the machine to act on stock of any thickness. The work support is represented as attached to the upper end of a rod 30 normally sustained by a spring which exerts sufficient tension to support the material, but not enough to interfere with the feeding of the stock. The rod sustaining the work support has combined with it aux-

iliary pressure means including a stronger 35 spring and a lever which, just prior to each action of the driver and the insertion of a fastening, acts through the stronger spring to sustain the work support substantially 40 rigidly while the fastening is being inserted. In case it should be desired to do what is called "monogram quilting," the 45 automatic feeding of the stock is preferably suspended by temporarily closing the feed opening of the work support, and at this 50 time a nut on the rod sustaining the work support is adjusted into such position that it may be struck at each operation of the machine by a device such, for example,

55 as a lever which partially releases the stock leaving it free to be moved by hand between the insertion of successive fastenings.

Figure 1 in elevation represents a part of the right hand side of a machine embodying 55 my invention. Fig. 1^a is a detail showing

the feed wheel in section and applied to the feed actuating shaft. Fig. 2 is a similar view of the lower part of the machine represented in Fig. 1, Figs. 1 and 2 together making a complete right hand side elevation. Fig. 3 is a detail looking at Fig. 2 from the left, said figure showing the treadles. Fig. 4 is a detail looking at the part of the machine shown in Fig. 2 from the right hand side. Fig. 5 is a front view 60 looking at the machine shown in Fig. 1 from the left. Fig. 6 is a rear view of the machine shown in Fig. 1. Fig. 7 shows the head detached from the neck or frame used to support it. Fig. 8 is a section in the line x^2 , Fig. 1. Fig. 9 is a section in the line x^3 , Fig. 8. Fig. 10 shows the face of the work support when a feeding device is to be used. Fig. 11 shows the cover for the work support employed in monogram work. 65

Referring to the drawings, A represents a column to stand on the floor, and A' a neck secured to the column and provided with bearings for the different operative parts of the machine to be described. The 70 neck presents an overhanging arm A² and an extended tubular arm A³. The arm A² is provided at its front end with ears A⁴ which constitute a seat for the head A⁵, shown detached in Fig. 7, said head constituting a guide for a driver bar a provided at its lower end with a driver a⁶ and at its upper end with a block a' free to be slid between vertical walls a² of said head, said block receiving a screw stud a³ carried by a link a⁴, said stud receiving upon its outside said block a nut a⁵. The link a⁴ is connected at its lower end to a crank pin a⁶ of a disk a⁷ attached to the shaft A⁸, the rotation of which shaft actuates the driver bar 75 80 85 90 95 positively in both directions.

The machine herein illustrated has two wheels 2, f² to feed a wire through a guide-way, f⁴ which wire is cut off at proper times for the formation of fastenings, the fastenings being thereafter placed in line with the driver to be driven into the stock. 100

The head A⁵ has a boss n, see Fig. 7, which receives, see dotted lines Fig. 1, and in section in Fig. 8, a rocking stud n' having at its outer end a pawl carrier n⁹ and to which is connected a pawl n⁸ adapted to engage a ratchet f' fixed to the feed-wheel 2. At its inner end said stud has an arm n² provided with a suitable roller or other stud n³ which 105 110

is normally kept pressed by a suitable spring n^5 toward a cam n^4 carried by the shaft A^8 . The rocker arm n^2 is provided with a feed regulator n^6 shown in Fig. 8 as a screw which is adjustable to contact sooner or later with the shoulder n^7 forming part of the arm A^2 to limit the extent of movement of the wire feeding mechanism.

The neck contains a bearing p pivoted at 10 p' for a shaft p^2 , herein represented as provided at its forward end with a stock feeding device shown as a wheel p^3 presenting two sets of teeth p^{3x} with a groove p^x between them, see Fig. 1^a, the object of the groove being to receive the point of each fastening as the same is driven if the length of the fastening should exceed the thickness of the stock, or in case one fastening should be driven on another. The shaft p^2 is sustained at its forward end back of said feed wheel in a movable bearing p^4 , see Figs. 1 and 8, said bearing having flat sides and being fitted to slide up and down and also longitudinally of a guideway p^5 formed in 20 the tubular arm A^3 . This bearing has extended from its end a curved flange 30 forming part of a case to be described, the other part of the case, see Fig. 5, being marked p^{12} and being connected with the portion 30 by screws 31. The upper portion p^{12} of the case constitutes a work support, said portion being slotted at its upper side, see Fig. 10, to enable the teeth of the feed wheel p^3 to project therethrough to engage the stock and feed the same over the work support. The portion p^{12} has a hole 30^x through which the driver may be inserted or withdrawn as will be described. The inner end of the bearing p^4 surrounds a reduced part of the shaft p^2 30 and abuts a shoulder of said shaft, see dotted lines Fig. 1. Just beyond the outer end of the bearing p^4 the shaft is again reduced, see Fig. 1^a, at p^{4x} and threaded, and the feed wheel p^3 is screwed onto the threaded end 40 of the shaft. The outer hub of the feed wheel is faced or made hexagonal, as represented in Fig. 5, that it may be engaged by a wrench or other device by which to screw the feed wheel firmly onto the shaft, and said hub is provided with a hole p^{2x} . Normally the hole 30^x in the part p^{12} of the case and the hole p^{2x} in the hub of the feed wheel occupy a position at one side of the line of movement of the driver, but whenever it is 50 desired to remove the driver from the driver bar or to insert a driver in said driver bar, the workman will slide the bearing p^4 to the right, viewing Fig. 1, taking with it the shaft, the feed wheel, and the work support, thus placing the holes 30^x and p^{2x} vertically in line with the driver, and thereafter the driver may be disconnected from the driver bar and drawn out through said holes. To provide for moving 60 the bearing p^4 and the shaft p^2 , as stated,

70 said bearing is provided at one side with a groove w^3 , in which is mounted a loose block w^4 , see Fig. 8, having a hole that is entered by an eccentric stud w^5 at the end of a rotating shaft w^6 . Said shaft w^6 has two flat surfaces w^7 , see Fig. 9, which are adapted to be engaged by a plunger w^{8x} , yieldingly sustained by a spring w^{7x} supported on an adjusting screw 40. The shaft w^6 has a handle w^{10} for imparting a rotary movement thereto when it is desired to move the bearing p^4 and is also provided with an annular groove that is entered by a washer w^8 which holds the shaft in place, said washer being held in position by a screw w^9 , as 80 shown in Fig. 9.

The bearing p^4 in which the work support is sustained receives the threaded end of a rod p^6 , see Figs. 1, 2 and 5, extended loosely through an enlarged hole in a part p^7 projecting from the column A. The rod p^6 has applied to it below the projecting part p^7 a collar p^8 which is held in adjusted position thereon by a clamp screw p^9 , the adjustment of said collar limiting the upward movement 90 of the work support and feed wheel toward the foot plate c^3 to thus prevent the contact of the points of the feed wheel with the underside of said foot plate. The rod p^6 has screwed upon it a second adjustable collar p^{14} which is retained in adjusted position by a set screw p^{14x} . The upper end of a spring p^{15} , sustained by a washer p^{16} resting upon a slotted ear p^{17} extended from the column A, acts on the underside of the collar p^{14} and serves normally to keep the work support and the feed device pressed upwardly with sufficient tension to enable said feed device to engage the stock with a force sufficient to move it over the work support 100 and between said work support and the underside of the foot plate when the feed device is rotated. The rod p^6 has clamped upon it below the ear p^{17} a third collar p^{18} , said collar being adjustable on said rod by 110 means of a screw p^{19} . The collar p^{18} is acted upon at its lower side by a strong spring p^{20} the lower end of which, see Fig. 2, rests on a collar p^{21} having a dependent lug p^{21x} which enters a notch between two ears 41 at the end of a lever p^{22} pivoted on a stud p^{23} sustained in the column A, said collar having depressions 42 which are entered by the rounded portions of said ears 41. Said lever has jointed to it at its opposite end a link p^{24} which is extended upwardly, see Figs. 1 and 2, and connected with a stud p^{25} of a rocking arm p^{26} mounted upon a stud p^{27} , see Figs. 1 and 6, said arm having extended from it a stud p^{28} 120 which is embraced loosely by the lower end of a link p^{29} having at its upper end a strap p^{30} surrounding an eccentric p^{31} , see dotted lines Fig. 6 fast on the shaft A^8 , said eccentric through the means described imparting 130

- to the lever p^{22} a continuous uniform stroke throughout the operation of the machine. The operation of the eccentric p^{31} is so timed as to raise the outer end of the lever p^{22} , 5 that it, acting through the collar p^{21} and spring p^{20} may put additional pressure on the work support just as and while a fastening is being driven into the work, at which time the work should be clamped.
- 10 When the machine is stopped, the eccentric occupies a position to place the outer end of lever p^{22} in its lowest position, at which time only the spring p^{15} acts to lift the rod p^6 and work-support, and at this time the operator to depress the work-support for the removal or insertion of work has only to 15 overcome the pressure of the single spring p^{15} .
- The lower end of rod p^6 is jointed by a 20 screw p^{33x} , see Figs. 2 and 3, with a foot treadle p^{33} fulcrumed on a long stud p^{34} , mounted in a bearing p^{35} connected with the foot of the column, the outer end of said lever having a right angled projection 100, 25 see Figs. 2 and 3, the depression of the free end of said treadle lowering the work support and feeding device whenever it is desired to remove and apply stock. A yoke-shaped foot treadle r is also mounted upon 30 stud p^{34} , said foot treadle having an extended arm r' to which is connected a spiral spring r^2 , the opposite end of said spring being connected with a projection r^3 extended from the column, another arm r^4 of said treadle, 35 see Fig. 4, having jointed to it at r^5 the lower end of a rod r^6 . The upper end of the rod r^6 carries a wedge block r^7 which controls in usual manner the engagement and disengagement of the clutch pulleys r^{10} and r^{12} to 40 stop or start the shaft A^8 which carries a pulley r^{14} that is driven by the belt r^{13} surrounding pulley r^{10} .
- The shaft p^2 is provided with a ratchet wheel t which is engaged and moved step 45 by step by a pawl t' preferably adjustably mounted, see Fig. 6, in the end of arm t^2 eccentrically connected by a screw t^3 with the end of the shaft A^8 , said pawl being reciprocated during each rotation of said 50 shaft. This pawl t' is connected with the arm t^2 by a suitable set screw t'^x , a suitable detent t^4 controlled by a spring t^{4x} acting to prevent retrograde movement of said shaft and its feed wheel.
- 55 In the operation of the machine described the stock or work is fed over the work support by the feed wheel, while the front end of the lever p^{22} is depressed or occupies a position to relieve the spring p^{20} from the 60 pressure of said lever, said spring acting it will be understood on the collar p^{18} , and while the stock is being fed only the lighter spring p^{15} exerts pressure just sufficient to enable the feeding device to properly engage 65 and move the work or stock over the work
- support. When a fastening is being inserted the work support needs to be held up more firmly to resist the thrust of the driver, and at such time the lever p^{22} is moved to act on the collar p^{21} and compress the strong spring p^{20} .
- I prefer to employ a rotatable feed wheel for feeding the stock, yet it will be understood that my invention would not be departed from should I substitute for said feed wheel any other well known equivalent feeding device.
- In case it is desired to quilt a monogram, for which work the movement of the stock is so varied that it could not be well 80 handled by the feeding device working automatically, I intend to remove the part p^{12} of the case and substitute for it a cover plate u , see Fig. 11, of the same shape but without the feed opening shown in the plate of Fig. 85 10. This cover presents a smooth surface upon which the under face of the stock rests, and the feed device is prevented from engagement with the stock. When the action of the feeding device is to be suspended for 90 monogram work, I rotate the collar 66 , see Fig. 2, on the threaded part of the rod p^6 below the lever p^{22} and raise said collar on said rod, putting the collar in such position that the left hand end of the lever p^{22} in the last part of each downward stroke will meet 95 said collar and act automatically to depress the rod p^6 and the work support sufficiently to release the work that the operator holding the same in his hand may move the 100 work freely in any direction.
- Having fully described my invention, what I claim and desire to secure by Letters Patent, is:—
1. In a machine for inserting fastenings, 105 a work support having a feeding device to engage and move the work over the work support, a rod coöperating with said work support, a spring acting constantly to sustain said work support, a stronger spring coöperating with said rod, and a device for compressing the stronger spring and moving said rod to clamp the stock while a fastening is being inserted.
  2. In a machine provided with a foot plate 115 to bear on the stock, the combination with a work support having a feeding device to engage and feed the work over said support, of a rod connected with said work support, a spring to raise the rod and work support, 120 and an adjustable collar on the rod to limit the extent of movement of the work support toward the foot plate.
  3. In a machine for inserting fastenings, 125 the combination with a work support having a feeding device, of a spring to sustain said work support, a stop to limit the upward movement of said work support, another spring acting to press said work support upwardly to clamp the stock while a fasten- 130

- ing is being inserted, and means to depress said work support automatically after the fastening inserting operation that the work may be fed over the work support by hand when doing monogram quilting.
5. In a machine of the class described, a work support, a shaft extended therethrough and provided with a feed wheel to engage the face of and feed the work over said support, means acting normally to press the work support and feed wheel upwardly, and means to increase the force of said upward pressure while a fastening is being driven.
10. In a machine of the class described, a vertically movable work support, means carried by the work support for feeding the work thereover, said means being movable with the work support, and means for effecting the vertical movement of said work support.
15. In a machine of the class described, a vertically movable work support, means carried by said work support for feeding the work thereover, said feeding means being movable with the work support, and means for effecting the vertical movement of said work support.
20. In a machine of the class described, a work support, a spring to sustain the same, feeding means carried by said work support to engage the face of and feed the work thereover, and a stop to limit the upward movement of the work support and feeding means.
25. In a machine of the class described, a vertically movable work support, means carried by said work support for feeding the work thereover, said feeding means being movable with the work support, and means for moving said work support together with the feeding means transversely to the path of its vertical movement.
30. In a machine of the class described, a work support provided with a slot, means for yieldingly sustaining the work support, a block mounted in said slot, and a shaft having an eccentric stud that enters an opening in said block, the rotation of the eccentric stud producing a sliding movement of the work support longitudinally of the main shaft of the machine.
35. In a machine of the class described, a work support, a shaft therein, a feed wheel connected with said shaft, a bearing in the work support for said shaft, a shaft having an eccentric stud co-operating with said bearing to slide it and the feed wheel shaft longitudinally of the main shaft of the machine, said stud shaft having flattened portions, and a retaining device co-acting with said flattened portions to retain said stud shaft and the work support in one or the other of its extreme positions.
40. In a machine of the class described, a work support having a detachable work receiving member, a feeding device to feed the work over said support, and means to press the work support and feeding device upwardly.
45. In a machine of the class described, a work support having a detachable work receiving member, a feeding device to feed the work over said support, and means to press the work support and feeding device upwardly.
50. In a machine of the class described, a work support, a shaft extended therethrough and provided with a feed wheel to engage the face of and feed the work over said support, means in said case to feed the work over said work support, a detachable plate having openings to allow the teeth of the feeding device to project therethrough, and actuating means for said toothed feeding device.
55. In a machine of the class described, a work support having a hole which in the operation of the machine is out of line with the driver, means to move said work support when the machine is stopped to place the hole in the work support in line with the driver that the latter may be withdrawn from the driver bar or a new driver to be inserted in the bar through said hole.
60. In a machine of the class described comprising a driver bar and a connected driver, a work support having a hole which in the operation of the machine is out of line with the driver, means to move said work support when the machine is stopped to place the hole in the work support in line with the driver that the latter may be withdrawn from the driver bar or a new driver to be inserted in the bar through said hole.
65. In a machine of the class described comprising a driver bar and a driver, a work support having a hole out of line with the driver when the machine is in operation, a feed device provided with a hub having a hole in line with the hole in the work support, means to move the work support and feed device to bring the holes therein in the line of movement of the driver that a driver may be detached from the driver bar and removed through said holes or a driver be inserted through said holes into the driver bar.
70. In a machine for inserting fastenings comprising a stationary foot plate, a shaft mounted in a pivoted bearing, means to rotate said shaft, a work support on said shaft at a distance from said pivoted bearing, a feed wheel carried by said shaft, and means to press said work support and feed wheel upwardly against the stock with a pressure sufficient to hold the stock against the foot plate while being fed, and means to increase the upward pressure of the work support on the stock while a fastening is being inserted.
75. In a machine of the class described, a vertically movable work support, feeding means carried by said work support and arranged to engage and move the work over the work support, yielding means acting continuously to maintain said work support in such relation to the work that the feeding means can act thereon, and means acting momentarily to bring a stronger pressure to bear upon the work support and work when the machine is acting upon the work.
80. In a machine of the class described comprising a foot plate, a work support, and feeding mechanism for feeding the work over the work support arranged to bear upon the work in the line of movement of the work support, a light spring acting continuously to press the work support toward the foot plate with a pressure sufficient to insure the feeding of the work by the feeding mechanism, additional means to increase the force of the pressure of the work support against the work while the fastening is being driven, and a foot treadle con-
85. In a machine of the class described comprising a driver bar and a driver, a work support having a hole out of line with the driver when the machine is in operation, a feed device provided with a hub having a hole in line with the hole in the work support, means to move the work support and feed device to bring the holes therein in the line of movement of the driver that a driver may be detached from the driver bar and removed through said holes or a driver be inserted through said holes into the driver bar.
90. In a machine of the class described comprising a driver bar and a driver, a work support having a hole out of line with the driver when the machine is in operation, a feed device provided with a hub having a hole in line with the hole in the work support, means to move the work support and feed device to bring the holes therein in the line of movement of the driver that a driver may be detached from the driver bar and removed through said holes or a driver be inserted through said holes into the driver bar.
95. In a machine for inserting fastenings comprising a stationary foot plate, a shaft mounted in a pivoted bearing, means to rotate said shaft, a work support on said shaft at a distance from said pivoted bearing, a feed wheel carried by said shaft, and means to press said work support and feed wheel upwardly against the stock with a pressure sufficient to hold the stock against the foot plate while being fed, and means to increase the upward pressure of the work support on the stock while a fastening is being inserted.
100. In a machine of the class described, a vertically movable work support, feeding means carried by said work support and arranged to engage and move the work over the work support, yielding means acting continuously to maintain said work support in such relation to the work that the feeding means can act thereon, and means acting momentarily to bring a stronger pressure to bear upon the work support and work when the machine is acting upon the work.
105. In a machine of the class described, a vertically movable work support, feeding means carried by said work support and arranged to engage and move the work over the work support, yielding means acting continuously to maintain said work support in such relation to the work that the feeding means can act thereon, and means acting momentarily to bring a stronger pressure to bear upon the work support and work when the machine is acting upon the work.
110. In a machine of the class described comprising a foot plate, a work support, and feeding mechanism for feeding the work over the work support arranged to bear upon the work in the line of movement of the work support, a light spring acting continuously to press the work support toward the foot plate with a pressure sufficient to insure the feeding of the work by the feeding mechanism, additional means to increase the force of the pressure of the work support against the work while the fastening is being driven, and a foot treadle con-
115. In a machine of the class described comprising a foot plate, a work support, and feeding mechanism for feeding the work over the work support arranged to bear upon the work in the line of movement of the work support, a light spring acting continuously to press the work support toward the foot plate with a pressure sufficient to insure the feeding of the work by the feeding mechanism, additional means to increase the force of the pressure of the work support against the work while the fastening is being driven, and a foot treadle con-
120. In a machine of the class described comprising a foot plate, a work support, and feeding mechanism for feeding the work over the work support arranged to bear upon the work in the line of movement of the work support, a light spring acting continuously to press the work support toward the foot plate with a pressure sufficient to insure the feeding of the work by the feeding mechanism, additional means to increase the force of the pressure of the work support against the work while the fastening is being driven, and a foot treadle con-
125. In a machine of the class described comprising a foot plate, a work support, and feeding mechanism for feeding the work over the work support arranged to bear upon the work in the line of movement of the work support, a light spring acting continuously to press the work support toward the foot plate with a pressure sufficient to insure the feeding of the work by the feeding mechanism, additional means to increase the force of the pressure of the work support against the work while the fastening is being driven, and a foot treadle con-
130. In a machine of the class described comprising a foot plate, a work support, and feeding mechanism for feeding the work over the work support arranged to bear upon the work in the line of movement of the work support, a light spring acting continuously to press the work support toward the foot plate with a pressure sufficient to insure the feeding of the work by the feeding mechanism, additional means to increase the force of the pressure of the work support against the work while the fastening is being driven, and a foot treadle con-

nected to the work support and adapted to lower the same, the parts being so timed that the machine stops only after its operation has been completed and with only the pressure of the light spring upon the work.

17. In a machine of the class described, a work support, feeding mechanism for feeding the work thereover, a rod connected thereto, a foot treadle connected to the rod, 10 a light spring continuously acting against said rod to hold the work support in contact with the work with a light pressure, a collar fast to the rod, a second, strong

spring surrounding the rod and engaging the collar, a second collar loose on the rod, 15 and a cam-controlled lever acting on said loose collar to momentarily apply strong pressure to said second spring and said rod while a fastening is being driven.

In testimony whereof, I have signed my 20 name to this specification in the presence of two subscribing witnesses.

ORRELL ASHTON.
